UNITED STATES PATENT OFFICE.

RICHARD DAVID METCALFE, OF ROMILEY, AND JAMES CROXON METCALFE, OF MARPLE, ENGLAND.

EXHAUST-STEAM INJECTOR.

Application filed May 24, 1921. Serial No. 472,085.

To all whom it may concern:

Be it known that we, RICHARD DAVID METCALFE, of The Mount, Romiley, Cheshire, England, and JAMES CROXON METCALFE, of Sheen Bank, Marple, Cheshire, England, both British subjects, have invented certain new and useful Improvements in Exhaust-Steam Injectors, of which the following is a specification.

10 This invention relates to exhaust steam injectors, that is the injectors which depend primarily upon a supply of exhaust steam at about atmospheric pressure but which can be worked by live steam throttled down to about atmospheric pressure, when exhaust steam is not available.

15 20 25

The object of our present invention is to provide improved means for supplying the throttled down live-steam when exhaust steam is not available, such means ensuring an even distribution of such steam at the inlet end of the steam inlet nozzle of the injector.

The invention comprises the improved combination and arrangement of parts hereinafter described and claimed.

Referring to the accompanying sheet of explanatory drawings which illustrate an exhaust injector having our invention applied thereto:—

Figure 1 is a sectional elevation and Figure 2 a part sectional plan view.

The same reference letters in the two views indicate the same parts.

35 The injector comprises a delivery nozzle *a*, a combining nozzle *b* with an opening and closing hinged flap *c* thereon, a water cone *d* and a steam nozzle *e*. Exhaust steam is admitted to the injector past the valve *f* which is fitted with an extension spigot *g* adapted to enter the valve seating ring *h* so as to ensure that the valve closes correctly when engaged by the cam *i*.

40 45 The nozzle *j* provides a supply of live steam at full boiler pressure to assist the exhaust steam when the latter is unable to provide a sufficient delivery pressure to feed the boiler to which the injector is fitted.

The valve *j'* controls the supply of steam to the nozzle *j*.

50 The supply of live steam which is throttled down to about atmospheric pressure by the valve *k'* and which is utilized to operate the injector when exhaust steam is not available, is obtained from the passage *k* having an outlet port at *m* and also an annular passage *n* around the steam nozzle *j* for the discharge of the steam. In order, however, to ensure a delivery of the steam from *k* into the steam space in advance of 60 the injector nozzles and in the direction of the nozzle *e* and passage *q* supplying steam to the space between the nozzles *d* and *c*, we provide the steam nozzle *j* with a projecting flange like ring *o* thereon and 65 through the said ring are drilled or formed a number of ports or nozzle-like apertures *p* by which the steam is directed into the nozzle *e*. Steam also diffuses into the injector through the space between the ring *o* and the face of the steam supply passage *k* and so ensures the supply for the passage *q*, the steam from the port *m* serves to prevent the formation of a vacuum around the valve *f*.

70 75 The arrangement before described of the ring *o* and ports *p* prevents the whole of the steam being projected towards the wall of the steam space opposite to that from which the passage *k* enters the said space.

We claim:

1. In exhaust steam injectors, in combination, exhaust steam, live steam, combining, and delivery nozzles, a valve controlling the inflow of exhaust steam, a passage admitting live steam throttled down to about atmospheric pressure, the live steam nozzle aforesaid extending through said passage, an annular steam delivery passage around the said live steam nozzle for throttled down live steam, and a ring with ports therethrough through and around which the steam from said annular passage is directed into the exhaust steam nozzle, as set forth.

2. In exhaust steam injectors, in combination, exhaust steam, live steam, combining,

and delivery nozzles, a valve controlling the inflow of exhaust steam, a passage admitting live steam throttled down to about atmospheric pressure, the live steam nozzle afore-
5 said extending through said passage, an annular steam delivery passage around the said live steam nozzle for throttled down live steam, and a ring with ports there- through upon the live steam nozzle through and around which the steam 10 from said annular passage is directed into the exhaust steam nozzle, as set forth.

In testimony whereof we have signed our names to this specification.

RICHARD DAVID METCALFE.
JAMES CROXON METCALFE.
